Dressing Millstones.

Patented Jan. 5, 1832.

Jan. 5, 1832

David Elam of Vanderburgh County, Indiana
Letters Patent.

The subscriber refers to my three letters Patent and making part of the same containing a description of the said David Elam himself of my improvement in the Mill stone.

To all to whom these presents shall come: I David Elam of the County of Vanderburgh and State of Indiana, have invented a new and useful improvement in the millstone for grinding grain and the following is a full and exact description of the construction and operation of the said improvement as invented or improved by me. The runner stone is round and hangs on a spindle which runs, horizontal as a groundstone with the face on the edge of circumference of the ground stone. The permanent or bed stone is set with an inverted circle to extend one third of the distance round the runner stone when not larger than 20 inches in diameter. 28 inches will fine it work, although it may be enlarged when you have power to put it in operation. The bed stone is set in a perpendicular position filling the lower part of the inverted circle close to the lower centre of the runner stone and letting it extend as far upwards as the edge will take it. Each stone is cut with four rows and lands, one contrary to the other so as to run shearing. The lands & furrows must be small and narrow. The runner stone must be furrowed with a draft from the center of the face to each edge, beginning at each edge and pointing towards the bed stone until both furrows meet calculating $1\frac{1}{4}$ inch draft on a stone a foot wide on the face, which is a proper width for a stone 20 inches in diameter. The bed stone must be furrowed with the draft contrary to the runner. The upper part of the bed stone must be drafted open to let grain gradually and close towards the bottom for flowing. The bed stone should be in strong opinion excepting the face. It must be confined between two timber permanent, yet so that it can be moved backwards and forwards as much as to grain new or fine, which is done by a hand with a scow in the lower not to drag it to its place, there may be a fly wheel attached to the spindle that runs the stone, like a cartwheel on the spindle and run by any common gear. The spindle must be left open some distance outside of the stone, there must be a counterpoise at about 5 inches from the spindle, on which

Jan 5, 1832

There is a mortise with a cattle stuff fixed in on a frame with one end extending over the square of the spindle while the other is attached to the other end extending to the side of the hopper drawing a strap over a pulley which strap extends through the shoe to the other side of the hopper, fastened to a spring. The shoe must be wide at the mouth to scatter the grain clear across the whole width of the stone. There must be a small edge made round the mouth of the stone, for the grain to drop in, out of the shoe to keep it from scattering. The spindle must only have two journals and that must be on each end. The stone, shallow and fly if one be attached, must all be between the journals.
